FISHING REEL

Morris E. Wood, Bronson, Mich., assignor to Higbie Manufacturing Company, Rochester, Mich., a corporation of Michigan

Filed Aug. 24, 1959, Ser. No. 57,265

Term of patent 14 years

(Cl. D31—4)

Fig. 1

Fig. 3

Figure 1 is a side elevational view of a fishing reel showing my new design, the opposite side being substantially the same, but without a handle;

I claim:

The ornamental design for a fishing reel, as shown and described.
